OF MASSACHUSETTS.

OIL-BURNING HEATER.

Application filed August 15, 1925. Serial No. 50,412.

This invention pertains to oil burning heaters of the constant level type in which the burner comprises a vertically movable bowl adjustable to vary the intensity of the flame, our invention relating more particularly to means for so supporting the burner bowl and connecting the fuel supply conduit thereto as to permit the bowl to move freely and without encountering substantial frictional resistance, and to means for automatically adjusting the bowl to vary the intensity of the flame.

While primarily intended to apply to burners of the movable bowl type, certain features of the invention, especially those pertaining to the automatic regulation, may, it is contemplated, be found of utility in connection with burners having means other than an adjustable bowl for varying the intensity of the flame.

We are aware that the automatic regulation of gas and electrical heaters is common and that automatic regulation of oil burners of large capacity such as are used for heating industrial steam boilers and so forth has been attempted, but we are not aware of any successful application of automatic regulating means to oil stoves or heaters of small capacity, such for example as oil ranges, water heaters, and the like, intended for domestic use and whereby the height of the flame may be regulated automatically either to increase or to decrease its intensity in accordance with the temperature of the medium, for example air or water, being heated.

We are also aware of so-called automatic regulators for small capacity stoves or heaters comprising springs, weights, or other energy storing means which are initially set by hand and thereafter automatically released to cut off the fuel supply or otherwise to extinguish the flame at the end of a predetermined time interval or when the medium being heated reaches a predetermined temperature but we wish to distinguish our present invention from the latter devices which we hold to be improperly termed "regulators", since they serve merely to extinguish the flame and not progressively to vary its intensity in accordance with temperature fluctuations in the medium being heated.

In furtherance of our object we provide for so supporting the burner bowl and for connecting the fuel supply conduit thereto that the bowl may move up and down with great ease and freedom, and we accomplish the automatic adjustment of this freely movable bowl by the provision of a thermal motor sensitively responsive to temperature fluctuations in the medium being heated and adapted to generate sufficient mechanical force to move the burner bowl to produce the requisite variations in intensity of the flame. Thus we may raise the temperature of the medium being heated to the desired degree and thereafter maintain it at such predetermined selected temperature without substantial variation.

Moreover we so combine this automatic regulating means with the usual hand control as to permit alternative use of either type of regulation without interference of one with the other, but preferably provide that the automatic regulating means shall take control, if for any reason the manual regulation is neglected and in consequence there is danger that the medium being heated will be raised to too high a temperature. Preferably also we provide that if, when under automatic control, the flame be entirely extinguished, further automatic movement of the burner bowl shall thereupon terminate in order to prevent subsequent lowering of the bowl and flooding of the unlighted wick with oil.

We find our invention to be particularly useful for regulating the heat of cooking ovens, domestic water supply tanks, and so forth, and we have herein illustrated it by way of example as embodied in a heater associated with such a water tank, a two burner heater having been selected for description herein.

In the drawings, Fig. 1 is a somewhat diagrammatic elevation to small scale showing the improved heater associated with a water supply tank having the usual supply and delivery connections;

Fig. 2 is a fragmentary vertical section to large scale substantially on the line 2—2 of Fig. 3 and showing details of the lower part of the heater;

Fig. 3 is a horizontal section substantially on the line 3—3 of Fig. 2;

Fig. 4 is a vertical section substantially on the line 4—4 of Fig. 3;

Fig. 5 is a perspective view showing the dial plate and a portion of the automatic controlling mechanism;

Fig. 6 is a plan view partly in section showing a portion of the fuel supply conduit;

Fig. 7 is a view similar to Fig. 6 showing a modified arrangement;

Fig. 8 is a diagrammatic elevation illustrating an embodiment of the invention somewhat different from that shown in preceding figures;

Fig. 9 is a fragmentary side elevation of the regulator housing;

Fig. 10 is a front elevation partly in section showing details of the regulating mechanism;

Fig. 11 is a fragmentary side elevation illustrating a modified arrangement permitting positive downward movement of the burner bowl; and

Fig. 12 is a fragmentary side elevation of a preferred form of control bar.

Referring to Fig. 1 of the drawings, the improved heater is designated generally by the character H, while the water tank associated therewith is indicated at T. This tank is furnished with the usual supply pipe 1 and with the outlet pipe 2 which leads to the inlet end of the heater. From the heater an outlet pipe 3 leads to a T 4 from one branch of which a pipe leads to the upper part of the tank T and from the other branch of which the delivery pipe 5 extends.

Referring more particularly to Figs. 2 and 3, the heater, which is here illustrated as having two burners, comprises a base 6 supported upon legs 7 and carrying the casing 8 which houses the regulating mechanism hereinafter to be described. The casing 8 supports a ring 9 which in turn carries a heater drum 10 of any usual construction.

The pipe 2 leading from the lower part of the tank T is connected with a short section 11 of pipe which passes through an opening in the rear wall of the casing 8 and which enters the lower part of a fluid receptacle 12. This fluid receptacle is preferably relatively tall and narrow and is disposed substantially at the center of the heater. The upper end of this receptacle 12 is connected to the usual heating coil or worm which is disposed within the upper part of the drum 10 but which is not illustrated herein. The upper end of the coil or worm is connected to the delivery pipe 3.

When the receptacle 12 and the coil are subjected to the heat generated by the burners the water contained therein is warmed and a circulation started which causes the cold water from the lower part of the tank to flow through the pipes 2 and 11 into the lower part of the receptacle 12 and thence

upwardly through the coil and the pipe 3 into upper part of the tank. The lower part of the receptacle 12 is thus constantly supplied with the coldest water in the circulating system.

The receptacle 12 is preferably furnished with a flanged base 13 (Fig. 3) which is connected by bolts or other suitable securing means to the upper wall 14 of a housing which forms a support for and encloses a portion of the regulator mechanism. This housing comprises spaced side walls 15 and 16 respectively, a rear wall 15^a and a short vertical front wall 16^a. The rear wall 15^a of this housing is connected by means of bolts 17 to the rear wall of the casing 8.

A bracket 18 is secured to the outer surface of the rear wall of the casing 8, preferably by means of the same bolts 17 which attach the regulator housing thereto. This bracket 18 is provided with a substantially horizontal arm which is connected at its rear edge at the point 19 to a substantially vertical leg 20 of the fuel supply conduit. Preferably the bracket 18 is secured to the leg 20 by spot welding, soldering or the like. The upper end of the tubular leg 20 supports the fuel supply reservoir 21 which is open at the top and which in turn supports an inverted fuel supply tank 22 from which the fuel feeds by gravity to the reservoir 21 under the control of barometric pressure.

The lower end of the leg 20 is preferably closed by means of a removable plug 23 and from a point intermediate the ends of the leg 20 a branch 24 extends toward the rear wall of the heater. This branch is united to a transversely extending pipe or tube 25 (Fig. 3) which may be attached to the rear wall 8 of the casing in any suitable manner.

The opposite side walls 15 and 16 of the regulator housing are provided with vertically spaced pairs of bearing openings 26, 27 and 28, 29—corresponding openings in the members 15, and 16 being aligned with each other. Preferably these openings are of key-hole shape, although this is not a necessary feature.

A link 30 is disposed at the outer side of the wall 16 of the regulator housing and has its rear end portion bent substantially at right angles to the main part thereof to form an axle member 31 which extends through the aligned openings 26 in the walls 15 and 16. At points near its engagement with the walls 15 and 16, the axle member 31 is preferably provided with outstanding lugs conveniently formed by striking up the metal. These lugs form limiting stops to prevent withdrawal of the axle member from the housing after it has been assembled therewith. In assembling the parts the axle 31 is so turned that these projections or lugs may be passed through the narrow portions of the key hole openings 26 and when the axle is

subsequently swung to its normal position these lugs are disposed adjacent to the circular portions of the openings so that an axle can not be accidentally withdrawn.

5 A second link 32 similar to the link 30 is disposed below the latter and is furnished with an axle member 32^a which extends through the openings 27 in the walls 15 and 16 and is retained in position in the same manner as the axle 31. The links 30 and 32 are bent outwardly at their forward ends to provide axle members 33 and 34 respectively which are parallel to their corresponding axle members 31 and 32^a respectively. 10 These axle members 33 and 34 are journaled in vertically spaced openings in a vertically elongate bracket 35 to which there is rigidly secured a hollow leg 36 forming a part of the fuel supply conduit. The upper end of 15 this leg 36 is connected to and supports burner bowl 37 which may be of usual construction and which in turn carries the usual chimney 38.

At the opposite side of the regulator housing links 39 and 40 (Fig. 4) similar to the links 30 and 32 are arranged. These links 39 and 40 are furnished with axle members 41 and 42 respectively which are journaled in the openings 28 and 29 respectively of the 20 side walls 15 and 16. The forward ends of the links 39 and 40 are bent outwardly to provide axle members 43 and 44, journaled in a bracket 45 which carries the tubular leg 46 supporting the other of the two burner bowls. The construction thus far described permits each burner bowl to rise and fall independently of the other, each bowl floating freely upon the outer ends of its pair of parallel supporting links.

40 In order to connect the fuel supply 25 to the leg 36 of the burner bowl without interfering to any substantial extent with the free rise and fall of the latter we preferably employ a tubular link 47 (Fig. 6) having its opposite ends bent as best shown in Fig. 6 to lie substantially perpendicular to the body of the link and parallel with each other. These bent portions are indicated at 48 and 49 respectively. The portion 48 passes through an axial opening in a cap 49' which closes the end of pipe 25 and through a packing ring 50, the inner end of the member 48 being outwardly flanged as indicated at 51. Similarly the member 49 of the link 47 passes through an axial opening in a cap 52 which closes the end of a short tubular branch 51' extending outwardly from the leg 36 and through a packing ring 53 within said cap, the inner end of the member 49 being outwardly flared at 54. The arrangement described provides a pivotal connection for each end of the link 47, and this pivotal connection may readily be made oil-tight by means of the packing rings 55 without imposing any substantial frictional

restraint upon the movement of the burner bowl, particularly since by reason of the length of the link 47 only slight angular movement occurs at the packing joints. The leg 46 of the other burner bowl is likewise connected to the pipe 25 by means of a pivoted tubular link 55 (Fig. 3) also having packed joints at its ends.

It is obvious that as links 30 and 32 are not pivoted in the same vertical plane as link 47 at the right hand end of each of these links as seen in Fig. 3, there will be a certain amount of necessary lost motion. This is small in any case due to the lengths and relative position of the links, but it is taken care of by providing the bearings at 26 and 27 with a loose fit. This same applies to the support for the other burner.

The walls 15 and 16 of the regulator housing are furnished with aligned openings 56 (Fig. 9) for the reception of a shaft 57. The ends of this shaft project outwardly beyond the side walls of the regulator housing and support respectively the rear ends of controlling levers 58 and 59. These levers may swing freely in a vertical direction about the shaft 57 as an axis and are connected to the shaft 57 somewhat loosely so that they may swing to a limited extent in a horizontal direction. The levers 58 and 59 project forwardly beyond the front of the casing 8 and are furnished at their forward ends with handles 60 and 61 respectively.

The forward wall of the casing 8 is furnished with an opening which is closed by means of a dial plate 62 (Fig. 5) preferably provided with a pair of forwardly projecting curved bosses 63 and 64. These bosses are provided with slots through which the forward ends of the levers 58 and 59, respectively, project. Preferably each of these slots is of substantially inverted U-shape and by swinging the corresponding lever horizontally it may be brought into alignment with either of the vertical legs of the corresponding slot. Preferably one leg 67 of each slot is somewhat shorter than the other leg 68 thereof. The longer leg 68 of each slot receives its corresponding lever while the burner bowl is under manual control and this longer leg is preferably furnished with a series of ratchet teeth 69 at one or both of its edges extending substantially from top to bottom thereof. The shorter leg 67, which receives the end of the controlling lever when the burner bowl is under automatic control, is preferably furnished with one or more ratchet teeth 70 at its upper part only, the lower part of this slot being smooth so that the lever may slide freely up and down therein.

Preferably the forward end of each of the control levers 58 and 59 is provided with a handle as above described, such handle (Fig. 2) being slideable longitudinally of the cor-

responding lever but being limited in its outward movement by a stop cap 610. The inner end of this handle is furnished with a ratchet engaging tooth or detent 611, and a spring 612 within the handle tends to force the handle rearwardly so as to engage this tooth or detent with the ratchet teeth of the dial plate.

Each of the levers 58 and 59 is furnished 10 respectively with an elongate slot 72 through which passes the corresponding axle member 34 or 44 of the levers 32 and 40 respectively. The control levers 58 and 59 are thus connected to the respective burner bowls and by 15 raising and lowering the ends of these levers and bowls may correspondingly be adjusted.

For manual adjustment of the burner bowls the forward end of the corresponding lever is placed in the long leg 68 of the slot 20 in the dial plate and when the burner is to be lighted the lever is pushed down to its lowermost position thus permitting free flow of fuel into the bowl. When the burner has been lighted the lever may be raised up 25 to a point indicated "High" on the dial plate and may be allowed to remain in this position so long as the maximum intensity of flame is desired. For decreasing the intensity of the flame the lever is raised gradually, thereby lifting the bowl and decreasing the fuel supply and when the lever reaches the upper end of the slot the fuel supply is substantially cut off and the flame is extinguished. Preferably a rest 71 is provided 30 for holding the control lever in the "out" position.

For automatically controlling the position of the burner when the lever engages the shorter leg 67 of the slot in the dial plate, we have provided a shaft 73 journalled at 40 its opposite ends in the side walls 15 and 16 respectively of the regulator casing, and upon this shaft we mount a tilting frame or lever 76 having spaced side members provided with openings 74 and 75 for the reception 45 of the shaft 73. The forward end of this tilting lever carries a transverse bar 77 disposed below the levers 58 and 59 and having its end portions disposed in the vertical planes of movement of said levers. Preferably the opposite ends of the bar 77 are of stepped formation (Fig. 10) providing 50 surfaces 78 and 79 arranged at different horizontal levels. The surface 79 lies in the plane of movement of the corresponding control lever when the latter is in the long leg 68 of the slot in the dial plate while the surface 78 lies in the path of movement of the lever when the latter is disposed in the shorter leg of the slot.

Preferably the end portions of the bar carrying the lower step surfaces 79 are bent to lie in a plane in front of the main body of the bar as shown in Fig. 12 at 79a.

The lower end of the receptacle 12 is pro-

vided with a screw-threaded opening which receives a threaded plug 80. The upper end 81 of this plug is of reduced diameter and projects up through the bottom of the receptacle 12 and enters the lower end of a tube 82 to which it is brazed or welded. This tube extends vertically up through the center of the receptacle 12 and is closed at its upper end by a plug 83.

The plug 80 forms a closure for the upper 75 end of a sylphon 84, the lower end of which is closed by a plug 85. This plug 85 is preferably furnished with a short tubular stop 86 disposed within the body of the sylphon and adapted to contact with the plug 80 to limit contraction of the sylphon. The plug 85 is provided with a central boss to which a cap 87 is connected. This cap is furnished with a transverse pin 88 whose opposite ends extend through openings 89 83 and 90 in the sides of the tilting frame 76, thus connecting the sylphon to said frame.

The sylphon 84 with the tube 82 constitutes a thermal motor which responds to fluctuations in temperature in the fluid contained in the receptacle 12 and by such response tilts the lever 76 up and down. The tube 82 is hereinafter referred to as a pressure generator and in assembling the apparatus this tube is partly filled with some 90 highly volatile liquid, for example ether, which responds very quickly to temperature changes in the surrounding fluid medium. The expansion or contraction of the vapor within the tube 82 produces mechanical movement of the plug 85 since the sylphon is capable of expanding or contracting longitudinally and the mechanical force thus generated is sufficient to raise and lower the burner bowl.

The upward movement of the plug 85 is limited by engagement of the stop tube 86 with the plug 80, such limitation of movement being desirable since the weight of the burner bowl tends to move the plug 85 110 upwardly.

The downward movement of the plug 85 is preferably limited by means of a yielding stop. For this purpose a bridge 91 is secured at its opposite ends to the side walls 115 15 and 16 of the regulator housing and has a guide opening for a vertically sliding bar 93 having a head 95 at its upper end disposed in the path of the lower end of cap 87. A spring 96 is interposed between the head 120 95 and the upper surface of the bridge 91. This spring may be tensioned by means of a nut 92 so as to oppose more or less resistance to the downward movement of the plug 85.

In Fig. 7 of the drawings a modified form of fuel conduit is illustrated comprising the tubular link 47a whose opposite ends are connected respectively to the supply pipe 25a and a boss 51a, carried by the leg 36 of the 130

burner bowl, by means of flexible tubular members 96^a. With this arrangement no joints whatever are necessary and since the fluid is under but slight pressure the tubular sections 96^a may be made very pliable so that but little resistance is opposed to the movement of the burner bowl.

In Fig. 8 we have shown diagrammatically a somewhat modified arrangement of the controlling mechanism, the burner bowl being designated by the character 37^b and its depending tubular leg by the character 36^b. The fuel reservoir 21^b is provided with a conduit member 24^b which is connected to the leg 36^b by means of the link 47^b having pivotal joints at 49^b and 52^b at its opposite ends, such joints being of the same type as shown in Fig. 6.

In this instance the link 47^b constitutes one of the supports for the burner bowl, the other support being provided by the controller lever 58^b which is pivotally supported at its rear end at a point 97 directly below the joint 49^b. This lever 58^b is pivotally connected at 98 to the lower end of the leg 36^b directly below the joint 52^b. Its forward end is provided with a handle 60^b and this lever may be engaged by a bar 77^b actuated by a thermal motor 84^b. This simpler construction eliminates the supporting links, since the burner bowl is supported solely by the conduit member 47^b and the controller lever 58^b.

In order that the burner bowl may be moved down positively by the thermal motor we provide the preferred arrangement shown in Fig. 11. In accordance with this arrangement a latch hook 100 is pivotally supported at 102 upon the lever 58. This latch hook is provided with a link 103 connecting it with the handle 60 and with a toe 101 adapted to engage an opening 104 in the cross bar 77. When thus engaged, downward movement of the cross bar positively pulls the lever 58 down and thus lowers the burner bowl. While this arrangement permits the thermal motor to be disconnected from the bowl by pulling downwardly from the handle 60, we contemplate permanent connections between the bowl and the thermal motor as falling within the scope of our invention.

The operation of the device of Figs. 1 to 7 is substantially as follows, it being assumed that the right hand control lever 58 was placed at the lower end of the slot 68 while the burner was being lighted and has then been lifted and swung over into the slot 67. When the controller lever is located in the lower part of the slot 67, the flame is at its maximum working intensity. As the water in the system gradually becomes warmer, the expansible fluid in the tube 82 expands and pushes the plug 85 downwardly. As the plug moves downwardly it swings the for-

ward end of the frame 76 up until the surface 78 of the cross bar 77 comes into contact with the control lever 58. Further movement of the plug 85 downwardly thus swings the control lever upwardly and raises the burner bowl. This decreases the fuel supply and cuts down the intensity of the flame. Ordinarily under such circumstances the water in the system will cease to rise in temperature and if its temperature begins to fall, then the contraction of the fluid within the tube 82, assisted by the weight of the burner bowl, tends to restore the latter to its lower position, thus again increasing the fuel supply and causing the flame to become hotter.

The range of movement of the lever 58 during such regulation takes place in the lower part of the slot 67 where there are no teeth 70 to interfere with its free movement. However, if, for example, when no water is being drawn from the system, the temperature of the water should continue to increase even after the bowl has been raised to the normal extent, the control lever will continue to rise until the fuel supply is entirely cut off and the flame is extinguished. In rising to this latter point the control lever enters that part of the slot 67 which is provided with teeth so that the dog 611 engages the teeth and prevents downward movement of the lever. As the water gradually cools and the plug 85 rises, the bowl is maintained in its uppermost position by the dog 611 and thus flooding of the wick with oil is prevented such as might take place were the bowl allowed to descend with the wick unlighted.

Since it is desirable to avoid complete extinguishment of the flame except under unusual circumstances, the adjustable stop 93 is provided which opposes the further downward movement of the plug 85 at a certain definite point in the travel of the latter. This stop 93 may be adjusted so as to determine the maximum rise of the bowl under ordinary circumstances thus preventing the fuel supply from being wholly cut off. However, as above pointed out, it may under some circumstances be desired to cut off the flame entirely and for this reason the stop is made yieldable so that when the pressure within the sylphon 84 exceeds a certain amount it will push the stop downwardly and thus raise the bowl to the point necessary to extinguish the flame.

The movement of the burner bowl is normally under manual control when the control lever occupies the slot 68 but it sometimes happens under such conditions that the user neglects to reduce the flame at the proper time so that the water tends to become excessively hot, at the same time wasting fuel. To prevent this from occurring the bar 77 is provided with the lower stop 79

which underlies the lever 58 when the latter is in the slot 68. During ordinary operation of the device the shoulder 79 is disposed below the path of movement of the lever 58 so that it does not interfere with manual control thereof. If, however, the heat becomes excessive and the plug 85 is pushed down to its extreme lowermost position, the bar 77 is raised sufficiently to engage the shoulder 79 with the lever 58 and lifts the latter to the upper part of its slot thus cutting down or wholly extinguishing the flame.

In the preferred arrangement of Fig. 12, the surface 79^a is so far forward of the surface 78 that it does not engage the lever 58 when positioned for lighting and so that it will not shut off the flame too soon.

While the operation has herein been described with respect to control lever 58, it is to be understood that the control 59 is similarly actuated both manually and automatically. Moreover, while the mechanism has herein been shown as embodied in a two-burner heater, it is obvious that the same number of operations and substantially the same mechanism may be employed in a single burner heater as well as in one having a greater number of burners than that herein shown. Furthermore we contemplate that in its broader features the invention is not necessarily limited to a burner having a movable bowl for controlling the flame but it is applicable to other types of flame control and we contemplate that the invention may be employed in other specific constructions wherein equivalent devices are substituted for the elements herein disclosed.

We claim:

40. 1. An oil burning heater of the class described comprising a burner of the maintained oil level type having a vertically movable bowl, a fixed fuel reservoir, a pair of substantially parallel links supporting and guiding the bowl in its movement, automatic means responsive to the temperature in the region of said burner for moving the bowl up and down, whereby to vary the level of the fuel therein and consequently to vary the intensity of combustion, and a fuel conduit connecting the reservoir and bowl comprising fixed end portions and a rigid median portion having flexible connections with the end portions.
45. 2. An oil burning heater of the class described comprising a burner having a vertically movable bowl, a fixed fuel reservoir, a conduit comprising members rigidly united to the bowl and reservoir, respectively, a rigid tubular link flexibly connected at its opposite ends to said rigid portions of the conduit, and thermally responsive means for automatically raising and lowering the bowl.
50. 3. An oil burning heater of the class de-

scribed having a vertically movable burner bowl, a fluid container so positioned relatively to the burner flame that its contents may be heated by the latter, said container having an inlet and an outlet, and a thermal motor comprising a pressure generator responsive to fluctuations in temperature of the fluid in the receptacle adjacent to the inlet thereof, said motor being connected to the bowl and adjusting the latter in accordance with pressure variations in the generator, whereby the intensity of the flame of the burner is simultaneously varied.

4. In combination with an oil burning heater of the class described having a vertically adjustable burner bowl, a fluid heating system comprising a receptacle so disposed relatively to the burner flame that its contents may be heated by the latter and set into circulation, and a thermal motor having a pressure generating element disposed within said receptacle adjacent to the inlet or cold end thereof, said motor being connected to the burner bowl and adjusting the position of the latter in accordance with fluctuations in temperature of the fluid within the receptacle, whereby the intensity of the flame of the burner is simultaneously varied.

5. In combination with an oil burning heater of the class described having an adjustable burner bowl, a fluid heating system comprising a tall and narrow vertically disposed fluid receptacle exposed to the flame of the burner, said receptacle having a cold fluid inlet near its lower end and a hot fluid outlet near its upper end, and a thermal motor responsive to fluctuations in temperature in the fluid entering the inlet of the receptacle and by such response adjusting the position of the burner bowl, whereby the intensity of the flame of the burner is simultaneously varied.

6. In combination with an oil burning heater of the class described having an adjustable burner bowl, a fluid heating system comprising a tall and narrow vertically disposed fluid receptacle exposed to the flame of the burner, said receptacle having a cold fluid inlet near its lower end and a hot fluid outlet near its upper end, and a thermal motor comprising a tubular pressure generator centrally disposed in the lower part of the receptacle where the temperature of the fluid is lowest and an expansible member outside of the receptacle but communicating with the generator and responding to changes in pressure in the latter, the motor being connected to the burner bowl and determining the position of the latter, whereby the intensity of the flame of the burner is simultaneously varied.

7. Regulating means for an oil burning heater of the class described having a vertically movable burner bowl, said means comprising a manually actuatable controller

and a thermally actuated controller, said controllers being alternatively operable to raise or lower the bowl.

8. Regulating means for an oil burning heater of the class described having a vertically adjustable burner bowl, said means comprising an element movable in response to fluctuations in temperature in the medium being heated, and a part connected to the bowl, said latter part being engageable with said movable element to transmit movements of the latter to the bowl, but being disengageable from said element at will, and manual means for adjusting the position of the bowl when the parts are disengaged.

9. Regulating means for an oil burning heater of the class described having a vertically adjustable burner bowl, said means comprising a member movable into a plurality of positions, said member being connected to the burner bowl, and when in one of said positions being movable manually to adjust the bowl, and an automatic controller effective in another position of said movable member to move the latter and thereby to raise or lower the bowl.

10. Regulating means for an oil burning heater of the class described having a vertically adjustable burner bowl, said means comprising a thermal motor, an element movable thereby in response to temperature fluctuations in the medium being heated, and a manually movable member for raising and lowering the burner bowl, said manually movable member being shiftable into and out of the path of the element which is moved by the thermal motor.

11. Regulating means for an oil burning heater of the class described having a vertically adjustable burner bowl, said means comprising a thermal motor, a lever connected to said motor and tiltable thereby in response to fluctuations in temperature in the medium being heated, and a manually movable member connected to the bowl for raising and lowering the latter, said manually movable member being shiftable into and out of the path of an element carried by the lever, said element, when in the path of the lever transmitting movement of the thermal element to the bowl.

12. Regulating means for an oil burning heater of the class described having a plurality of burners each having a vertically movable bowl, said means comprising a thermal motor responsive to temperature fluctuation in the medium being heated, and means for transmitting motion from the motor to any or all of said burner bowls at will whereby automatically to regulate the flame of the burner or burners to which such motion is transmitted.

13. Regulating means for an oil burning heater of the class described having a pair of spaced burners each having a vertically

movable bowl, a thermal motor exposed to the medium heated by the burners and responsive to temperature fluctuations in such medium, a supporting member for each burner bowl, said supporting members being vertically movable to raise or lower their respective bowls, a transversely extending bar below said supporting members and means connecting the bar to the motor whereby movement of the latter may be transmitted to both of said levers.

14. Regulating means for an oil burning heater of the class described having a pair of spaced burners each having a vertically movable bowl, a thermal motor exposed to the medium heated by the burners and responsive to temperature fluctuations in such medium, a pair of spaced parallel levers, means connecting said levers respectively to the respective burner bowls, a handle for manually raising and lowering each lever with its bowl, a bar disposed below said levers with its opposite end portions extending transversely across the vertical planes of movement of the respective levers, and means connecting the bar to the thermal motor to be moved by the latter.

15. Regulating means for an oil burning heater of the class described having a vertically adjustable burner bowl, said means comprising a thermal motor and a lever connected thereto, the motor responding to fluctuations in temperature in the medium being heated and thereby tilting the lever in one direction or the other, said lever having a part provided with step-like surfaces, and a member connected to the bowl for raising and lowering it, said member being positionable at will in the path of movement of any selected one of said step-like surfaces.

16. Regulating means for an oil burning heater of the class described having a pair of spaced burners each having a vertically movable bowl, a thermal motor exposed to the medium heated by the burners and responsive to temperature fluctuations in such medium, a pair of spaced parallel levers, means connecting said levers respectively to the respective burner bowls, a handle for manually raising and lowering each lever with its bowl, a bar disposed below said levers, said bar having step-like end surfaces, and means connecting the bar to the thermal motor for bodily movement by said motor, the levers being independently movable in a horizontal direction to dispose them respectively in position by engagement by any selected one of the step-like surfaces of the corresponding end of the bar.

17. Regulating means for an oil burning motor of the class described having a vertically adjustable burner bowl, said means comprising a thermal motor and a lever connected thereto, the motors responding to

fluctuations in temperature in the medium being heated and thereby tilting the lever in one direction or the other, said lever having a part provided with step-like surfaces, a bowl supporting lever provided with a handle, and means connecting the supporting lever to the burner bowl, said supporting lever being movable in a vertical direction to raise or lower the bowl and being also movable in a horizontal direction to position it in the path of movement of a selected one of said step-like surfaces.

18. Regulating means for an oil burning heater of the class described having a vertically movable burner bowl, said means comprising a manually actuatable controller for raising and lowering the bowl, and a thermal controller also adapted to raise and lower the bowl, said controllers normally operating alternatively, said automatic controller, whether the bowl be under manual or automatic control, being operative to raise the bowl to extinguish the flame when a predetermined temperature in the medium being heated is exceeded.

19. Regulating means for an oil burning heater of the class described, having a burner provided with a vertically movable bowl, a thermal motor exposed to the medium heated by the burner and responsive to temperature fluctuations in said medium, a vertically movable controller member provided with a handle, means connecting the burner bowl to the controller member, a dial plate having a slot of substantially inverted U-shape, the controller member passing through the slot and being shiftable laterally to engage either of the vertical legs of the slot, and means engageable with the controller member, when disposed in one of the legs of the slot, automatically to move the controller member up or down.

20. Regulating means for an oil burning heater of the class described having a burner provided with a vertically movable bowl, a thermal motor exposed to the medium heated by the burner and responsive to temperature fluctuations in said medium, a vertically movable controller member provided with a handle, means connecting the burner bowl to the controller member, a dial plate having a slot of substantially inverted U-shape, the controller member passing through the slot and being shiftable laterally to engage either of the vertical legs of the slot, one of said legs being longer than the other, the longer leg having ratchet teeth extending along the greater portion of one of its edges and the shorter leg having such teeth near its upper part only, and automatic means for raising and lowering the controller member when disposed in the shorter leg of the slot.

21. Regulating means for an oil burning heater of the class described having a burner

provided with a vertically movable bowl, a thermal motor exposed to the medium heated by the burner and responsive to temperature fluctuations in said medium, a lever pivoted adjacent to one of its ends and adapted to swing in a vertical plane and also in a horizontal direction, means connecting the burner bowl to the lever at a point intermediate the ends of the latter, a dial plate having a slot therethrough, said slot comprising spaced parallel legs, the free end of the lever projecting through the slot, a detent carried by the free end of the lever, ratchet teeth at one edge of one leg of the slot with which said detent may be engaged to retain the lever in selected elevated position whereby normally to determine the position of the burner bowl, and automatically actuated means engageable with the lever when its forward part is disposed in the other leg of the slot to determine the position of the bowl in accordance with the temperature of the medium being heated.

22. Regulating means for an oil burning heater of the class described having a burner provided with a vertically movable bowl, a thermal motor exposed to the medium heated by the burner and responsive to temperature fluctuations in said medium, a lever pivoted adjacent to one of its ends and adapted to swing in a vertical plane and also in a horizontal direction, means connecting the burner bowl to the lever at a point intermediate the ends of the latter, a dial plate having a slot therethrough of substantially inverted U-shape, the free end of the lever projecting through the slot, a handle slidably mounted on the forward end of the lever, said handle having a detent element at its inner end, ratchet teeth at the edge of one leg of the slot with which the detent element may be engaged to retain the lever in elevated position, and a thermal motor for moving the lever up and down when the lever is disposed in the other leg of the slot.

23. Regulating means for an oil burning heater of the class described having a burner movable to regulate the intensity of the flame and an element for moving said burner, an automatic controller connected to said element for moving the latter to increase or decrease the intensity of the flame, and means operative, when the flame has been extinguished by the action of said controller, to lock said movable element in fixed position.

24. Regulating means for an oil burning heater of the class described having a burner provided with a vertically movable bowl, a thermal motor exposed to the medium heated by the burner and responsive to temperature fluctuations in said medium, a vertically movable controller member provided with a handle, means connecting the burner bowl to the controller member, a dial plate

- having a slot of substantially inverted U-shape, the controller member passing through the slot and being shiftable laterally to engage either of the vertical legs 5 of the slot, means engageable with the controller member when disposed in one of the legs of the slot automatically to move the controller member up and down, and means engageable with said controller member 10 when moved above a predetermined point to prevent its return to a lower position.
25. Regulating means for an oil burning heater of the class described having a burner provided with a vertically movable bowl, a 15 thermal motor exposed to the medium heated by the burner and responsive to temperature fluctuations in said medium, a vertically movable controller member provided with a handle, means connecting the burner bowl to the controller member, a dial plate having a slot of substantially inverted U-shape, the controller member passing through the slot and being shiftable laterally to engage either of the vertical legs of 20 the slot, a thermal motor responsive to temperature fluctuations in the medium being heated, means for transmitting movement from the motor to the controller member when the latter is disposed in one leg of 25 the slot, said leg having ratchet teeth at one edge engageable with the controlling member when lifted to a predetermined degree to prevent its return to a lower position.
26. Regulating means for an oil burning 30 heater of the class described having a movable flame controlling element, automatic motive means for moving said element to increase or decrease the intensity of the flame, and stop means tending to limit movement of said element in reducing the intensity of the flame, said stop means yielding to insistence of said motive means and thereby permitting the element to move sufficiently completely to extinguish the flame.
- 45 27. Regulating means for an oil burning heater of the class described having a movable flame controlling element, said means comprising a thermal motor exposed to the medium heated by the burner and responsive to temperature fluctuations in said medium, 50 means connecting the thermal motor to the flame controlling element, automatically to raise and lower the flame, and means opposing a substantial resistance to further movement of the motor when the flame has 55 been reduced to a predetermined degree.
28. An oil burning heater of the class described having a vertically movable burner bowl, a thermal motor responsive to temperature fluctuations in the medium heated by the burner flame and by its response moving the bowl up or down, and an adjustable yielding stop normally operative to limit upward movement of the bowl but yielding to abnormal force exerted by the 60 motor to permit the bowl to rise beyond said normal limit.
29. Regulating means for an oil burning heater of the class described having a movable flame controlling element, said means 65 comprising a thermal motor exposed to the medium heated by the burner and responsive to temperature fluctuations in said medium, means connecting the thermal motor to the flame controlling element automatically to raise and lower the flame, and a resiliently yielding stop device tending to stop further movement of the motor when the flame has been reduced to a predetermined degree, said stop yielding to permit 70 subsequent further movement of the motor sufficient completely to extinguish the flame if the temperature of the medium being heated fails to decrease responsive to such previous reduction of the flame.
